HUBERT A. MYERS, OF TOLEDO, OHIO, ASSIGNOR OF ONE-HALF TO ARTHUR S. HICKOK,
OF TOLEDO, OHIO

RAILROAD CROSS-PAVEMENT CONSTRUCTION

Application filed April 12, 1929. Serial No. 354,456.

My invention has for its object to provide a metal pavement that may be readily taken up and replaced and, consequently, is of particular value in connection with railroad crossings, where it is necessary to frequently adjust railroad beds and replace ties, which makes the ordinary pavement of railroad crossings exceedingly expensive in view of the fact that such pavements have to be torn up and replaced each time the track or the bed is repaired. This invention particularly relates to the provision of a convenient means whereby the parts of the pavement may be readily removed. The cast iron parts of the pavements which embody my invention are for covering the ends of the ties and portions of the bed located on the outside of the ends of the ties.

The invention may be contained in pavement constructions that vary in their details, and, to illustrate a practical application of the invention, I have selected one of such pavement constructions as an example of the various embodiments of my invention and shall describe the pavement construction selected hereinafter. The pavement structure is shown in the accompanying drawings.

Fig. 1 illustrates a perspective view of a railroad crossing having the parts embodying my invention. Fig. 2 is an edge view of one of the parts of panels containing the invention. Fig. 3 is an end view of the part illustrated in Fig. 2. Fig. 4 is a perspective view of one of the parts inverted. Fig. 5 is a view of a section taken on the plane of the line 5—5 indicated in Fig. 2. Fig. 6 is a perspective view of a part of the pavement formed by assembly of the parts illustrated in Figs. 2, 3, and 4.

The cast iron parts 1 are used for covering the ends of the ties 2 and on the outside of the rails 3. Each of the parts is provided with a pair of legs 4 that are, preferably, pyramidal in form to give them strength. The lower end surfaces 5 of the legs 4 are, preferably, shaped to conform to the angle of the surface 6 of the base 7 of the rail and the edge of the part 1 at the end where the legs 4 are located is provided with a surface 8 that fits the side 9 of the top 10 of the

rail. The legs 4 are provided with inclined surfaces 11 that conform to the under side surfaces 12 of the top 10 of the rail 3. The surfaces 8 and 11 are continuous in that they fit the side and under surfaces 9 and 12 of the top 10 of the rail 3, so as to locate the corner 13 of the pavement part 1 substantially in the corner 14 of the rail 3, while the lower ends of the legs 4 rest upon the base 7 of the rail.

In order to hold the pavement part 1 in this position, a support rail 15 is located on the outside ends of the ties 2 and in position to support the outer ends of the parts 1 so that the top surfaces of the parts 1 will be located substantially in the plane of the top surface of the rail 3. The auxiliary rails 15 have a head, or an enlarged top portion 16, a flange or web 17 and a base 18. The web and the base preferably form an L-shaped metal structure, the base 18 extending towards the rail 3 and secured by suitable spikes on opposite sides of the rail 15. The under side of each of the pavement parts 1 is provided with a pair of hooks or slotted ears 19 and 20, one located at a point slightly remote from one corner and having the outwardly extending engaging hook 21 and the other located at the other corner and having the inwardly engaging hook 22. The engaging parts 21 and 22 are located a distance from the under side of the pavement part 1, substantially equal to the height or thickness of the head or top portion 16 of the auxiliary rail 15. Thus, in order to secure the pavement parts in position, they are located at an angle to the auxiliary rail and so that the auxiliary rail will extend in a diagonal position relative to the part 1 and, when the part 1 is turned so as to locate the side edges of the part 1 at right angles to the rails 15, the hook or slotted ear 19 will engage the inside of the web 17 and the under side of the head 16, while the hook or engaging ear 22 will engage the outside of the web 17 and the under side of the head 16. Thus, the parts 1 are located in succession in position along the rails 3 and 15, or, if desired, a certain number of the parts may be slid along the rails and one of the parts may be turned angularly to

unlock the connection between the hooked ears 19 and 20 with the rail 15, and removed. As many of the pavement parts may thus be removed as may be desired to enable the performance of any desired operations upon the track or the bed. They may then be readily replaced and the other pavement parts slid into position as required.

In order to lock the parts in position, the 10 first and last of the parts are provided with downwardly extending webs 25 which terminate in laterally extending flanges 26 that may be located on the ends of two of the ties 2. Railroad spikes 27 may be driven into the 15 tie so as to engage the flanges 26 and lock the end parts of the pavement construction in position and, consequently, lock all of the other pavement parts in position.

Preferably the parts are provided with 20 sloping surfaces 30 to locate the surfaces of the portions of the parts 1 in vicinity of the rails 3 below the surfaces of the top of the rails, to insure clearance of these parts from the wheels of the trains that move over the 25 tracks.

I claim:

1. In a pavement member formed of metal and having surfaces that conform to the base and the sides of the rails, an auxiliary rail 30 for supporting the outer end of the pavement part, the part having a pair of hooked members for engaging the opposite sides of the auxiliary rail and beneath the head of the auxiliary rail.

2. In a metal crossroad pavement construction comprising a plurality of metal parts, each part having portions for resting on the base of the rail and for engaging the under side surfaces of the tops of the rails, a support rail, each part having hooked members for engaging the opposite sides of the support rail and the under side of the head of the support rail for securing the surfaces of the opposite ends in contact with the corresponding surfaces of the rail of the railroad track.

3. In a metal crossroad pavement construction comprising a plurality of metal parts, each part having portions for resting on the base of the rail and for engaging the under side surfaces of the tops of the rails, a support rail, each part having hooked members for engaging the opposite sides of the support rail and the under side of the head of the support rail for securing the surfaces of the opposite ends in contact with the corresponding surfaces of the rail of the railroad track, the end parts having flanges located on the ties to lock the parts of the pavement construction.

In witness whereof I have hereunto signed my name to this specification.

HUBERT A. MYERS.
